SLIDE BOLT ACTION FOR FIREARMS

Samuel L. Hampton, La Mesa, Calif.

Application February 1, 1957, Serial No. 637,790

2 Claims. (Cl. 42—16)

This invention relates to an improved slide bolt action for such as rifles.

The primary object of the invention is to provide a safer, more reliable, and more easily operated slide bolt action of this kind which is simple in construction, is composed of a small number of simple and easily assembled parts, and which involves laterally or radially spreadable locking heads on the forward end of the bolt assembly which engage in a locking groove in a rear end portion of the barrel of such a rifle immediately behind the cartridge chamber thereof, so as to strongly and positively lock the bolt assembly against rearward displacement by firing of a cartridge in the cartridge chamber.

Another object of the invention is to provide a bolt assembly of the character indicated above which involves spring-positioned means for gripping the rim of a fired cartridge and pushing the cartridge laterally out of an ejection slot in the bolt action housing in which the bolt assembly operates.

Another object of the invention is to provide a bolt action of the character indicated which is readily and economically manufactured, is easily installed and maintained, and is highly satisfactory and safe in operation.

These together with other objects and advantages which will become apparent reside in the details of construction and operation as more fully hereinafter described and claimed, reference being had to the accompanying drawings forming a part hereof, wherein like numerals refer to like parts throughout the several views, and in which:

Figure 1 is a top plan view of a rifle incorporating a bolt action of the present invention;

Figure 2 is a side elevation of Figure 1;

Figure 3 is an enlarged fragmentary vertical longitudinal section taken substantially on the plane of line 3—3 of Figure 1, showing the bolt assembly and a cartridge in firing position;

Figure 4 is a fragmentary vertical transverse section taken substantially on the plane of line 4—4 of Figure 3;

Figure 5 is a fragmentary vertical transverse section taken substantially on the plane of line 5—5 of Figure 3;

Figure 6 is a vertical longitudinal section similar to Figure 3, looking from the opposite side of the rifle from that shown in Fig. 3, showing the bolt assembly retracted to ejection position;

Figure 7 is a horizontal sectional view taken substantially on the plane of line 7—7 of Figure 6, showing the bolt assembly in retracted ejection position preliminary to being moved forwardly to eject a cartridge; and,

Figure 8 is an enlarged exploded group perspective view of the novel bolt action.

Referring to the drawings in detail, indicated generally at 10 is a rifle having a stock 12, in barrel 14, and a bolt action housing 16, in which works a sliding bolt action 18, and a trigger housing 19 in which is a trigger assembly 20. The stock 12 comprises a shoulder engaging portion 22 and a pistol grip portion 24, said portion 24 continuing in a forwardly extending vertically slotted housing portion 26 receiving therein the trigger housing 19 in which is incorporated a magazine receiver 16 positioned forwardly of the trigger assembly 20. The portion 26 continues in a forestock 28 reciprocably supporting thereon, in any suitable manner, an actuating or

2

pump sleeve 30 for cocking the rifle and for loading and ejecting cartridges, said forestock 28 being supportably engaged with the underside of the barrel 14.

The barrel 14 comprises a forward portion 32 having a rifled bore 33 which is enlarged at its rear end to define a shouldered cartridge chamber 36. The barrel 14 has an enlarged diameter rear end or breech portion 34 in which the cartridge chamber 36 is located and which includes a rearwardly extending reduced diameter portion 38 defining with the portion 34, a stop shoulder 40. The cartridge chamber 36 opens at its rear end in an enlarged diameter annular recess 42 which extends to the rear end of the portion 38 and has intermediate its ends an annular locking groove 44 in its sidewall. The bolt housing 16 terminates at its forward end in a sleeve 46 which is engaged on the reduced diameter portion 38 of the barrel portion 34 and is secured in place thereon by a locking and orientating screw 48 traversing the sleeve 46 and threaded in a bore 47 in the underside of the portion 34 of the barrel.

The portion 26 of the stock 12 has therein a downwardly opening slot 50 into which the trigger housing 19 is engaged, beneath a rearward portion 52 of the bolt housing 16, and the portion 52 has a downwardly opening slot 54 communicating with the open upper end of the trigger housing 19. An upwardly opening positioning recess 55 in the stock portion 28 receives the head 49 of the screw 48, so as to orientate the barrel 14 in its proper position on the stock 12.

The trigger assembly 20 comprises a suitable frame 56 mounted in the trigger housing 19, and comprising forwardly and rearwardly extending plate portions 58 and 60, respectively, which are traversed by vertical front and rear tang bolts 62 and 64, respectively, threaded upwardly into the under part of the bolt housing 16. As seen in Figure 3, the front tang bolt 62 extends through the sleeve 46 and is threaded into the under part of the barrel portion 34. The upper end of the rear tang bolt 64 is threaded in a socket 65 in the rear end portion of the bolt housing 16. The sidewall of the bolt housing 16 has therein a longitudinally extending ejection slot 66 on one side thereof, as shown in Figure 6.

The frame 56 of the trigger housing 19 has on its forward end a rectangular opening 67 for receiving a suitable cartridge magazine 69. The frame 56 supports at its forward end a transverse pivot pin 68 on which is a depending spring-urged latch bar 70 whose lower end is engageable with the rear end of the magazine 69 for releasably retaining the magazine in place. Rotatably mounted on the pivot pin 68 is a hammer 72 whose head 73 is movable upwardly and forwardly into the bolt housing 16, as indicated in dotted lines in Figure 3. The hammer 72 incorporates a depending lug 74 having circumscribed thereon the upper end of a retracting or cocking spring 76 whose lower end is engaged in a recess 78 in the frame 56. The hammer 72 has a depending sear lug 80 which is engageable by a trigger, as hereinafter described, and a rearwardly extending safety latch shoulder 82. Extending transversely of the frame 56, behind the hammer 72, is a pivot pin 84 on which is pivoted a depending trigger 86 having a forwardly extending sear engaging lever 90 whose forward end 91 is engageable with the sear lug 80 of the hammer 72. The lug 80 has a rearwardly and downwardly extending angular portion 92 for wedgingly engaging the forward end 91 of the lever 90. The pivot pin 84 has circumscribed thereon a helical hair-spring 94 having a rear arm 96 engaging a rearwardly projecting rear lug 98 on the trigger 86. Rearward movement of the trigger 86 results in forward movement of the hammer 72 to the dotted line position shown in Figure 3 for striking the firing pin of the bolt assembly 18. Slidably supported on the frame 56 is a safety

lock 100 incorporating a retaining yoke 102 which is engageable over the shoulder 82 of the hammer 72 when the lock 100 is moved forwardly, so as to preclude firing movement of the hammer 72 from its locked position.

The bolt housing 16 incorporates a longitudinally extending cylindrical bore 104 communicating with the open upper end 54 of the trigger housing 19, in which is reciprocably engaged the bolt assembly 18. The bolt assembly 18 comprises an operating and cam sleeve 106 having a bevelled forward end 108, and a longitudinally elongated slot 110 which is located near its rear end 109, and which communicates with the bore 112 of the sleeve 106. Extending laterally and downwardly from intermediate portions of the sleeve 106 are portions 114, one of which is clearly shown in Figure 8, which are on the rear ends of forwardly extending longitudinally elongated driven bars 116 which are secured at their forward ends 118 to the opposite sides of the pumps or actuating slide 30, on the forestock 28 of the rifle stock 12. Thus, longitudinal movement of the slide 30 results in longitudinal movement of the sleeve 106 and the remainder of the bolt assembly 18, in opposite directions. The movement of the bolt assembly 18 is rectilinear, that is, without twisting or rotation thereof in moving from a retracted position to a forward firing position.

Circumposed on the sleeve 106 is a locking sleeve 120 which has an annular external ring portion 130 near its rear end 131 and four circumferentially spaced longitudinal slots 132 defining therebetween four greater cylindrical resilient spring fingers 124. On the forward ends of the fingers 124 are external locking heads 126. The locking heads 126 have inner cam surfaces 128 which are engageable by the bevelled forward end 108 of the sleeve 106 for spreading the locking heads 126.

The ring portion 130 on the locking sleeve 120 is intersected by the slots 132. The ring portion 130 provides means for orientating the locking sleeve 120 with an outer carrier sleeve 134, as hereinafter described, and a transverse bore 136 extends through the ring portion 130 and the sleeve 120. The driven bars 114 extend through slots 132 of the sleeve 120. Circumposed on the sleeve 120 is the outer sleeve 134 having in its sidewall two longitudinally extending slots 136 which open through the forward end 138 and receive therein the driven bars. The outer sleeve 134 has a hole 140 in its sidewall near its rear end 135, through which extends a countersunk locking screw 142. The bore 133 of the sleeve 134 has a forwardly flaring end portion 144 which enables spreading of the fingers 124 and of the locking heads 126, within the sleeve 134, and engagement of the heads 126 into locking position in the annular locking groove 44 in the barrel portion 34.

As clearly seen in Figure 3, the locking heads 126 reach laterally beyond the sleeve 134 and into the groove 44 and lock the bolt assembly 18 in its forward firing position behind a cartridge C contained in the cartridge chamber 36.

Engaged within the cam sleeve 106 is a firing pin tube 146 having on its forward end an external enlarged annular end portion 148 for engagement in the recess 42 of the barrel portion 34, against the shoulder 149 thereof. The forward end of the portion 148 has therein a cylindrical recess 150 for receiving the rim of a cartridge C in the cartridge chamber 36. The firing pin tube 146 has in its sidewall, near its rear end 151, a threaded hole 152 in which the inner end of the screw 142 is threaded, see Figure 7. Sliding in the bore 154 of the tube 146 is a firing pin 156 having a rear end 158 extending beyond the rear end 151 of the tube 146, see Figure 7, but disposed forwardly of the rear end 109 of the cam sleeve 106 when the bolt assembly is in its retracted position. The rear end 158 of the firing pin 156 is exposed for engagement by the head 73 of the hammer 72, see Figure 3, when the bolt assembly 18 is locked in its forward firing position. The firing pin 156 has in one side

thereof an elongated longitudinally extending groove 162 into which the inner end 143 of the screw 142 extends, see Figure 7, so that the firing pin can move longitudinally and forwardly relative to the tube 146 for firing a cartridge C. The bore of the tube 146 has intermediate its ends a partition wall 164 having a relatively small axial bore 145 therethrough in which slides a reduced diameter elongated pin portion 166 on the forward end of the firing pin 146, whose forward end strikes the primer of a cartridge C, as shown in Figure 3, when the hammer 72 is operated. Circumposed on the pin portion 166 and compressed between the firing pin 156 and the partition wall 164 is a helical compression spring 168 which urges the firing pin rearwardly away from engagement with the cartridge C.

In the forward end of the portion 148 of the firing pin tube 146 and in communication with the bore 154 is an enlarged socket 150.

Sliding in the bore 154 forwardly of the partition wall 164 is a cylinder lock 172 retained in place by means of a screw 174 engaged in a longitudinal groove 175 in the side of the cylinder and limiting reciprocal movements of the cylinder in the bore 154, see Figure 3. A helical compression spring 176 is circumposed on the firing pin portion 166 and is compressed between the partition wall 164 and the rear end of the cylinder 172. The cylinder 172 constitutes a component of ejection means for ejecting fired shells of cartridges C, as seen in Figure 7. Pivoted mounted on the portion 148 of the tube 146 is a laterally inwardly extending spring-urged dog 180 for engaging the front side of the rim on the rear end of a shell casing of a cartridge C and swinging the shell casing laterally and out of the ejection slot 66 in the bolt housing 16, as the bolt assembly 18 is retracted, as seen in Figure 7, to react the position shown in Figure 6.

Forward movement of the bolt assembly 18 produced by sliding of the sleeve 30 forwardly on the forestock 28 moves the entire bolt assembly forwardly toward the firing position shown in Figure 3. As the bolt assembly thus moves forwardly a cartridge C, projected from the magazine 69 by its spring 71 into the bolt housing portion 52 in front of the bolt assembly is urged forwardly into the cartridge chamber 36, as shown in Figure 3. The annular ring portion 148 of the firing tube 146 is then disposed in the annular recess 42, and further forward movement of the cam sleeve 106 causes forward movement thereof relative to the firing pin and the firing pin tube 146. The sleeve 106 moves forwardly relative to the locking sleeve 120 so that the cam end 108 engages the inner sides 128 of the locking heads 126 and spreads the heads 126 into the locking groove 44, so as to securely lock the bolt 18 against rearward displacement upon the firing of a cartridge C. With a cartridge C in the cartridge chamber 36, the cylinder 172 is rearwardly displaced, against the resistance of the spring 176, and the dog 180 is displaced to engage around the rim of the cartridge. Rearward movement of the bolt assembly after a cartridge has been fired results in movement of the locking heads 126 inwardly of the outer periphery of the outer sleeve 134, the cam sleeve 106 having sufficient movement relative to the locking sleeve 120 by virtue of the elongated slot 110 in the sleeve 106. When the bolt assembly 18 reaches the retracted position shown in Figure 7, the shell of the cartridge C is pushed forwardly and laterally by forward movement of the cylinder 172 by the spring 176, and the dog 180 serving as a fulcrum, the cartridge shell is ejected through the slot 66.

The foregoing is considered as illustrative only of the principles of the invention. Since numerous modifications and changes will readily occur to those skilled in the art, it is not desired to limit the invention to the exact construction and operation shown and described, and accordingly all suitable modifications and equiva-

lents may be resorted to, as fall within the scope of the appended claims.

What is claimed as new is as follows:

1. In a sliding firearm bolt action, a barrel having a rear end portion having therein a rearwardly opening cartridge chamber, a bolt housing at the rear end of the barrel having a bore aligned with said cartridge chamber, a stock on which the barrel and the bolt housing are mounted, a trigger assembly mounted on the stock rearwardly of the cartridge magazine, a cartridge magazine receiver on the stock forwardly of the trigger assembly and opening into the bolt housing bore, a slide mounted on the stock, a bolt assembly sliding in the bolt housing bore behind the barrel, said bolt assembly comprising an outer sleeve sliding in said bore, said outer sleeve having a forwardly flaring bore portion, a locking sleeve engaged in said outer sleeve having longitudinal spring fingers having laterally projecting locking heads on their forward ends projecting laterally outwardly from the outer tube at the forward end thereof, said locking heads having internal cam surfaces, an operating and cam sleeve sliding in said locking sleeve and having a cam on its forward end operatively engageable with the locking head cam surface, means operatively connecting said operating sleeve to said slide, a firing pin tube sliding in said operating tube, an enlarged diameter ring portion on the forward end of said firing pin tube positioned forwardly of the forward end of the operating sleeve, said firing pin tube having a bore extending axially therethrough and said ring portion having an enlarged axial recess in its forward end for receiving the rim on the rear end of a cartridge positioned in said cartridge chamber, an internal partition wall in the bore of the firing tube and spaced from the ends of the firing tube, said partition wall having a reduced axial bore therethrough, a firing pin sliding in the firing pin tube rearwardly of the partition wall and having a reduced pin portion working in said reduced axial bore, spring means urging the firing pin rearwardly, said firing pin having a rear end and said trigger assembly having a hammer head arranged to be engaged with the rear end of the firing pin to project the reduced firing pin portion to strike and fire a cartridge in the cartridge chamber, a forwardly spring pressed cylinder slidably mounted on said reduced firing pin portion forwardly of said partition wall, means for limiting longitudinal movement of said cylinder along said reduced pin portion, said cylinder having a forward cartridge engaging end, means connecting the outer sleeve, the locking sleeve and the firing pin sleeve together against rotation and longitudinal movements relative to each other, and limiting longitudinal and rotational movements of the operating and cam sleeve relative to the operating sleeves and precluding longitudinal and rotational movement of the firing pin tube relative to the operating and cam sleeve, said rear end portion of the barrel having therein an annular recess opening in the bolt housing bore and accommodating said enlarged ring portion of the firing pin tube in the forward firing position of the bolt assembly, said recess having a shoulder at its forward end, the sidewall of said annular recess having therein an annular locking recess into which said locking heads are engageable when the operating and cam sleeve is moved forwardly relative to the locking sleeve, with the enlarged ring portion of the firing pin tube engaged with said shoulder, and the cam of the operating sleeve engages the cam surface of the locking heads and spreads the heads into said locking groove.

2. In a sliding firearm bolt action, a barrel having a rear end portion having therein a rearwardly opening cartridge chamber, a bolt housing at the rear end of the barrel having a bore aligned with said cartridge chamber, a stock on which the barrel and the bolt housing are mounted, a trigger assembly mounted on the stock rearwardly of the cartridge magazine, a cartridge magazine

70
75

receiver on the stock forwardly of the trigger assembly and opening into the bolt housing bore, a slide mounted on the stock, a bolt assembly sliding in the bolt housing bore behind the barrel, said bolt assembly comprising an outer sleeve sliding in said bore, said outer sleeve having a forwardly flaring bore portion, a locking sleeve engaged in said outer sleeve having longitudinal spring fingers having laterally projecting locking heads on their forward ends projecting laterally outwardly from the outer tube at the forward end thereof, said locking heads having internal cam surfaces, an operating and cam sleeve sliding in said locking sleeve and having a cam on its forward end operatively engageable with the locking head cam surface, means operatively connecting said operating sleeve to said slide, a firing pin tube sliding in said operating tube, an enlarged diameter ring portion on the forward end of said firing pin tube positioned forwardly of the forward end of the operating sleeve, said firing pin tube having a bore extending axially therethrough and said ring portion having an enlarged axial recess in its forward end for receiving the rim on the rear end of a cartridge positioned in said cartridge chamber, an internal partition wall in the bore of the firing tube and spaced from the ends of the firing tube, said partition wall having a reduced axial bore therethrough, a firing pin sliding in the firing pin tube rearwardly of the partition wall and having a reduced pin portion working in said reduced axial bore, spring means urging the firing pin rearwardly, said firing pin having a rear end and said trigger assembly having a hammer head arranged to be engaged with the rear end of the firing pin to project the reduced firing pin portion to strike and fire a cartridge in the cartridge chamber, a forwardly spring pressed cylinder slidably mounted on said reduced firing pin portion forwardly of said partition wall, means for limiting longitudinal movement of said cylinder along said reduced pin portion, said cylinder having a forward cartridge engaging end, means connecting the outer sleeve, the locking sleeve and the firing pin sleeve together against rotation and longitudinal movements relative to each other, and limiting longitudinal and rotational movements of the operating and cam sleeve relative to the operating sleeves and precluding longitudinal and rotational movement of the firing pin tube relative to the operating and cam sleeve, said rear end portion of the barrel having therein an annular recess opening in the bolt housing bore and accommodating said enlarged ring portion of the firing pin tube in the forward firing position of the bolt assembly, said recess having a shoulder at its forward end, the sidewall of said annular recess having therein an annular locking recess into which said locking heads are engageable when the operating and cam sleeve is moved forwardly relative to the locking sleeve, with the enlarged ring portion of the firing pin tube engaged with said shoulder, and the cam of the operating sleeve engages the cam surface of the locking heads and spreads the heads into said locking groove, and a spring-urged cartridge rim engaging dog mounted on the enlarged ring portion of the firing pin tube so as to engage around the rim of a fired cartridge in the cartridge chamber, said dog operating in conjunction with forward spring urged movement of said cylinder against the rear end of the cartridge as the bolt assembly is moved toward retracted position by operation of said slide, to swing the cartridge laterally out of an ejection slot formed in a sidewall of said bolt housing.
